UNITED STATES PATENT OFFICE.

CHARLES L. MICHOD, OF CHICAGO, ILLINOIS.

WALL STRUCTURE.

Application filed December 11, 1920. Serial No. 429,921.

To all whom it may concern:

Be it known that I, CHARLES L. MICHOD, a citizen of the United States, residing at Chicago, in the county of Cook and State 5 of Illinois, have invented a new and useful Improvement in Wall Structures, of which the following is a specification.

My invention, generally stated, relates to the art of constructing wall structures, 10 either forming the parts of buildings, or otherwise.

As to one phase of my invention, it consists in improvements in the constructing of walls made of slabs of concrete or other 15 relatively heavy material, and as to another phase of the invention it relates generally to wall structures formed of bodies which are arranged in edge-to-edge relation to form the wall.

20 One of my objects is to reduce the cost of constructing wall structures, more particularly when formed of slabs, as for example concrete; to provide for the proper sealing of the joints between the slabs; to 25 permit of the use of a lighter framework, especially in the case of buildings, to which the slabs are secured, and still present the desired rigidity of structure; to generally improve upon structures of the character 30 referred to; and other objects as will be manifest from the following description.

Referring to the accompanying drawings:

Figure 1 is a face view of a wall structure, which may be a wall of a building, 35 constructed in accordance with my invention, a portion of one of the slabs being broken away at two different places. Figure 2 is a broken, enlarged, section taken at the line 2-2 on Fig. 1 and viewed in 40 the direction of the arrow. Figure 3 is a section taken at the line 3-3 on Fig. 1 and viewed in the direction of the arrow. Figure 4 is a view like Fig. 1 and of the structure therein shown, with the slabs removed. 45 Figure 5 is the same as Fig. 3 except that it is enlarged and shows a portion only of the structure represented in Fig. 3; and Fig. 6, a broken, enlarged, section taken at the 50 line 6-6 on Fig. 1 and viewed in the direction of the arrows.

In the particular construction shown, and in connection with which I have chosen to illustrate my invention, the wall is formed of a framework preferably of metal 55 and slabs, or panels of concrete, or any

other suitable material, arranged in edge-to-edge relation and tied to the framework. The framework shown is formed of uprights 7 located at the ends of the wall, intermediate uprights 8 spaced apart from each other and from the uprights 7 preferably equidistantly, three of these intermediate uprights being shown, though it will be understood that the invention is not limited to this particular number of uprights, 60 and cross-pieces 9 extending lengthwise of the wall structure and shown as arranged in three tiers. All of these frame members are preferably formed of metal bars, the uprights 7 being shown as I-beams, the intermediate uprights being shown as formed each of two angle irons 10 rigidly connected together at their rearwardly-extending flanges, and having their other flanges 65 extending in opposite directions in line with 70 the wall, and the cross-members 9 being of angle shape in cross-section, these cross-members fitting in between the uprights 8 and between the latter and the uprights 7, the cross-members 9 being secured in position, as by plates 10^a suitably secured, as, 75 for example, by rivets to the rear faces of the laterally-extending flanges of the intermediate uprights 8 and the uprights 7, and to the depending flanges 11 of the cross-bars 80 9, each of the latter being provided with a series of holes 12 in the depending flanges 11 thereof, these holes being preferably 85 equidistantly spaced.

The framework described co-operates with 90 a foundation of any desirable kind, such as that represented at 13 and which may be formed of concrete, and preferably, especially in the case of buildings, is at least partially imbedded in the ground. The 95 uprights 7 are anchored to the foundation 13 in any desirable manner, as for example by bolting them thereto at the feet 14 provided on the lower ends of the uprights 7, the intermediate uprights 8 being shown 100 as resting on the upper surface of the foundation.

The panels are represented at 15 and are preferably of the reenforced, pre-cast, type. As shown, these slabs are relatively high, as 105 compared with their width, and the reenforcement therein is formed of a series of wires 16 extending substantially parallel with each other and in spaced relation, the long way of the slab, with wires, represent- 110

ed at 17 and preferably extending parallel with each other and at a right angle to the wires 16, extending crosswise of the slab, the wires 16 and 17 being preferably tied together at their intersections, by wires as represented at 18. Cast in the slab are plates 19 which extend crosswise thereof and are spaced apart vertically to correspond with the vertical spacing of the cross-members 9, these plates containing apertures 20 through which bolts 21 also cast in the slab, extend, the threaded ends of these bolts extending beyond the rear face of the slab. The bolts 21 are spaced apart to correspond with the spacing of the openings 12 in the cross-pieces 9, whereby when the slabs are applied to position against the framework as hereinafter stated, the protruding ends of the bolts 21 will register with the openings in the cross-members 9 and through which latter they extend, nuts 22 being then applied to the ends of the bolts to rigidly secure the slabs to the framework.

25 In the erecting of the wall, the framework referred to being in position, the slabs 15 are set up on end on the foundation 13, to the position shown wherein they extend in edge-to-edge relation, and are then fastened in place to the framework as stated. The arrangement of the parts of the structure is such, as shown, that the force exerted downwardly by the slabs, is taken by the foundation 13 by reason of the support 30 of the slabs at their lower ends on the foundation, the framework referred to being provided primarily for the purpose of maintaining the slabs in upright position.

35 Provision is made for rendering the wall structure continuous from end to end by tying adjacent slabs together. This may be accomplished in any desirable manner, but preferably in the way shown which involves the formation of the upright edges of the 40 slabs, except the outermost edge of each of the end slabs, with a substantially V-shaped channel represented at 23, the wires 17 being of such length that they extend into the respective channels to a position in which, 45 when the slabs are assembled with each other as stated, they overlap adjacent the ends of these wires, as represented more particularly in Fig. 6. After the slabs have been positioned as stated, any suitable cementitious 50 material, as for example cement, is run into the spaces provided by the opposing channels 23, thereby imbedding therein the ends of the wires 17, the material referred to binding the slabs together and sealing the 55 joints therebetween.

60 It will be understood from the foregoing that by constructing a wall structure in accordance with my invention the same may be made continuous and of practically uniform strength.

The supporting of the slabs directly on a rigid support, as distinguished from hanging them on a frame, presents the great advantage of permitting a wall structure to be constructed presenting the desired resistance to deflection, but with a lighter frame than hitherto provided, whereby the production of the structure is rendered much more economical. Furthermore, the arrangement shown acts to very effectually stiffen the 70 framework, which is of advantage where, as oftentimes in the case of buildings, the framework is required to support objects or structures other than the wall itself.

75 It will be understood that in the case of buildings where the wall is to be of greater height than the longest dimension of the slabs, the superposed tier or tiers of slabs would be supported at their lower ends on a relatively solid support, as for example bars 80 extending from one end upright to the other and connected therewith, as distinguished from hanging slabs on the framework, which would thus require the framework to be sufficiently heavy to support the slabs.

85 While I have illustrated and described a particular construction embodying my invention, I do not wish to be understood as intending to limit it thereto as the same may be variously modified and altered, and 90 the invention take other forms, within my invention.

95 What I claim as new, and desire to secure by Letters Patent, is:

100 1. A wall structure formed of an upwardly-extending framework, bodies arranged in edge-to-edge relation extending upwardly and flatwise opposing a face of said framework, a member adapted to support said bodies at their lower ends independently of said framework, and means connecting said bodies with said framework.

105 2. A wall structure formed of a framework extending upwardly, pre-cast slabs or the like of concrete or the like material, arranged in edge-to-edge relation and extending upwardly and flatwise opposing a face of said framework, a member adapted to support said slabs at their lower ends independently of said framework, and means 110 connecting said slabs with said framework.

115 3. A wall structure formed of a framework comprising end uprights, a foundation to which said end uprights are anchored, bodies arranged in edge-to-edge relation and extending upwardly and flatwise opposing a face of said framework, said bodies being supported at their lower ends on said foundation, and means connecting said bodies with said framework.

120 4. A wall structure comprising a framework formed with members, said framework being apertured at intervals, bodies arranged in edge-to-edge relation and opposing said framework, said bodies being pro- 125

vided with a series of projecting members which register with the said openings in the frame, upon the application of said bodies to said framework.

5. A wall structure comprising a framework formed with members extending longitudinally of the wall and apertured at intervals, bodies arranged in edge-to-edge relation and opposing said framework, said bodies being provided with a series of projecting members which register with the said openings in the frame, upon the application of said bodies to said framework.

6. A wall structure comprising a framework formed with members, said framework being apertured at intervals, and pre-cast slabs of concrete, or the like, arranged in edge-to-edge relation and opposing said framework, said slabs containing members imbedded therein and projecting beyond a face thereof, which register with the said openings in the framework upon applying the said slabs to said framework.

7. A wall structure comprising a framework formed with members extending longitudinally of the wall and apertured at intervals, and precast slabs of concrete, or the like, arranged in edge-to-edge relation and opposing said framework, said slabs containing members imbedded therein and projecting beyond a face thereof, which register with the said openings in the framework upon applying the said slabs to said framework.

8. A wall formed of a series of bodies

arranged in edge-to-edge relation, members projecting beyond the edges of said bodies, said bodies being so formed as to present a channel between adjacent bodies into which said members extend, and self-hardening plastic material located in said channels and imbedding said members.

9. A wall formed of a series of bodies arranged in edge-to-edge relation, members projecting beyond the edges of said bodies, said last-referred-to edges containing grooves, the grooves of adjacent edges registering to form a channel between adjacent bodies into which said members extend, and self-hardening plastic material located in said channels and imbedding said members.

10. A wall structure formed of a series of bodies having reinforcing members arranged therein, said bodies being arranged in edge-to-edge relation and said members extending beyond the said edges of the slabs, the opposed faces of said bodies presenting a channel into which said reinforcing members extend, and self-hardening plastic material located between adjacent edges of said bodies and imbedding said members.

11. A slab of concrete, or the like, for forming a wall, said slab containing a plate imbedded therein and containing apertures into which studs imbedded in the slab extend, said studs extending beyond a face of the slab.

CHARLES L. MICHOD.
